VALVE ACTUATOR FOR FLOOR FURNACES

Robert W. Mueller, Milwaukee, and Herbert G. Bernsee, Wauwatosa, Wis., assignors to Milwaukee Gas Specialty Company, Milwaukee, Wis., a corporation of Wisconsin

Application March 31, 1939, Serial No. 265,224

2 Claims. (Cl. 251—150)

This invention relates to floor furnaces, and refers particularly to gas fired floor furnaces, and especially to the means for controlling the flow of fuel thereto.

5 Floor furnaces are constructed to be set into the floor and have a register at the floor level through which the heated air enters the room, and in some instances, through portions of which cold air is returned to the furnace. The furnace 10 extends down a substantial distance beneath the floor level, and inasmuch as the best location for the burner is in the lower portion of the furnace, it is expedient to likewise mount the valve which 15 controls the flow of gas to the burner near the bottom of the furnace.

To control the valve, a stem extends upwardly therefrom to the floor level where an actuating handle is mounted to be readily accessible for manual actuation. Heretofore, however, the construction of the valve actuating mechanism has been such that a downward force applied to the actuating stem either during actuation thereof or by stepping on the actuating handle, was transmitted directly to the rotatable plug of the valve, 25 and as a consequence, the plug was very often mechanically frozen.

This invention therefore has as one of its objects to provide an improved manner of actuating the valve whereby a downward force imposed 30 on the actuating handle cannot be transmitted to the rotatable plug.

Another object of this invention is to provide means for preventing the transmission of downward force onto the valve plug, which is so designed that no modification is necessary either 35 in the design of the valve or the furnace.

With the above and other objects in view which will appear as the description proceeds, this invention resides in the novel construction, combination and arrangement of parts substantially as hereinafter described, and more particularly defined by the appended claims, it being understood 40 that such changes in the precise embodiment of the hereindisclosed invention may be made as come within the scope of the claims.

The accompanying drawings illustrate two complete examples of the physical embodiment of the invention constructed in accordance with the best modes so far devised for the practical 45 application of the principles thereof, and in which:

Figure 1 is a perspective view of a conventional floor furnace, illustrating the application of this invention thereto;

Figure 2 is a side view of the fuel control valve

and the actuating mechanism therefor, shown enlarged and with parts thereof broken away and in section;

Figure 3 is a top view of the valve;

Figure 4 is an enlarged longitudinal sectional view through a modified embodiment of the invention; and

Figure 5 is a perspective view of the elements of the construction shown in Figure 4, disassembled.

Referring now particularly to the accompanying drawings in which like numerals indicate like parts, the numeral 5 designates a floor furnace of any conventional construction, which, as is customary, is set into an opening in the floor 15 6 so that the entire furnace lies beneath the floor level. Across the top of the furnace is a floor register 7 through which the heated air rises into the room and through portions of which cold air may be returned to the furnace. The 20 construction of the furnace per se forms no part of this invention, and therefore, is not shown.

The heat source in furnaces of this nature is generally provided by a gas burner (not shown) supplied with fuel from a supply line 8 in which 25 a valve or cock 9 is interposed. Inasmuch as the burner is located in the lower portion of the furnace, it is expedient to likewise position the valve or cock at the bottom of the furnace.

The valve or cock, as best shown in Figures 2 30 and 3, comprise a body 10 having an inlet 11 connected with the supply line 8, and an outlet 12 from which a duct 13 leads to the burner. Between the inlet and outlet, the body has a 35 downwardly tapered vertical bore 14 in which a plug 15 is rotatable.

It is to be observed that the upper edge of the plug 15 lies beneath the upper face 16 of the valve body, and that only a reduced central stud 17 projects up from the plug above the face 16. 40 This central stud provides means by which the plug may be turned, which is accomplished through the medium of a stem 18 which extends up from the valve to the floor level, being guided at its upper end by a hole 19 in the floor register. 45

An actuating handle 20, which may be in the form of a removable key, nonrotatably but removably fitted to the upper end of the stem, provides means for manually turning the stem. Its lower end has a collar 21 fixed thereto by means 50 of a pin 22. This collar fits loosely over the stud 17 and has slotted apertures 23 in its opposite side walls to receive the ends of a cross pin 24 fixed to the stud 17. In this manner, a non-rotatable but longitudinally movable driving con-

nction is established between the stem and the valve plug which precludes accidental disengagement of the actuating stem from the plug.

The collar 21 also has a wall 21' spaced from the outer end of the stud 17 which positively prevents the stem 18 from contacting the stud. Inasmuch as the wall 21' is spaced from the end of the stud 17 and as the bottom of the collar 23' rests on the face 16 of the valve body, and not on any portion of the plug, any downward force applied to the actuating handle is transmitted directly to the valve body and not to the rotatable plug. Consequently, it is impossible to freeze the plug by the application of a severe downward force, either as an incident to manual actuation of the handle 20, or by accidentally stepping on it.

Provision is also made to control the flow of fuel to a pilot light (not shown). This is effected through the medium of a cock 25 fed from the inlet side of the main valve and passing the fuel to a duct 26 which leads to the pilot light.

The cock 25, like the main valve, comprises a rotatable tapered plug 27 mounted in a bore 28 and having a stud 29 projecting up from its upper end. An actuating stem 30 extends from the cock 25 to the floor level with its lower end non-rotatably joined to the stud 29 in identically the same manner as the stem 18 is joined to the rotatable plug 15. The upper end of the stem 30, like the stem 18, is shaped for the reception of the key 20 so that the same actuator key may be used for actuating both valves.

Another manner of coupling the actuating stem to the rotatable valve plug is illustrated in Figures 4 and 5. In this embodiment of the invention, the rotatable plug 15 has a central stud 31 projecting from its upper end and protruding through the cap 16 threaded on the upper end 40 of the body.

The actuating stem 18 has a coupling 32 fixed thereto and is nonrotatably though loosely connected with the stud 31 through a cross pin 33 fixed in the stud and engaging in a longitudinal slot 34 in the lower end of the coupling.

Disassembly of the parts is prevented by means of a snap ring 35 engaged in an annular groove 36 in the bore 37 of the coupling. This snap ring extends across the slot 34 to engage the pin 33 and prevent separation of the coupling 32 from the stud 31.

It is to be observed that the bore 37 into which the stud 31 extends is larger than the stud to allow for a degree of relative motion, and that the lower end of the coupling rides on the cap 16 to preclude the application of downward force on the rotatable plug.

From the foregoing description taken in connection with the accompanying drawings, it will be readily apparent that this invention provides a novel manner of controlling the supply and pilot valves in a gas fired floor furnace by which freezing of the plugs through the application of excessive downward force on the actuating handle is entirely obviated, and that this desirable result is achieved without the need for modification in the design or construction of the furnace or the valves.

What we claim as our invention is:

1. In a valve of the character described: a valve body having a tapered bore with the large diameter end of the bore opening to the exterior of the body at the top side thereof; a tapered plug rotatable in said bore; a cover secured to the valve body in a position covering the open end of the bore and the large diameter end of the plug, said cover having a top wall provided with an aperture aligned axially with said tapered bore; a central stud on the large diameter end of the plug extending through said aperture so as to project above the top wall of the cover; an actuating stem having one end adjacent to the central stud of the valve; a coupling secured to said end of the actuating stem and having a bore to freely receive the projecting end of the central stud while allowing the coupling to rest on the adjacent top wall of the cover; a nonrotatable driving connection between the coupling and the stud comprising, a pin transversely secured in the stud and projecting into a longitudinal slot in the coupling, said slot permitting a substantial degree of longitudinal motion of the coupling and actuating stem with respect to the valve stud, the engagement between the coupling and the top wall of the cover limiting such motion in one direction and preventing the application of downward force from the stem to the plug; and means on the coupling engageable with said pin for limiting longitudinal motion of the coupling and actuating stem in the other direction, said means also serving to prevent detachment of the pin from the slot.

2. In a valve of the character described: a valve body having a tapered bore with the large diameter end of the bore opening to the exterior of the body at the top side thereof; a tapered plug rotatable in said bore; a cover secured to the valve body in a position covering the open end of the bore and the large diameter end of the plug, said cover having a top wall provided with an aperture aligned axially with said tapered bore; a central stud on the large diameter end of the plug extending through said aperture so as to project above the top wall of the cover; an actuating stem having one end adjacent to the central stud of the valve; a coupling secured to said end of the actuating stem and having a bore to freely receive the projecting end of the central stud while allowing the coupling to rest on the adjacent top wall of the cover; a nonrotatable driving connection between the coupling and the stud comprising, a pin transversely secured in the stud and projecting into a longitudinal slot in the coupling, said slot permitting a substantial degree of longitudinal motion of the coupling and actuating stem with respect to the valve stud, the engagement between the coupling and the top wall of the cover limiting such motion in one direction; and a spring ring secured in the bore of the coupling below the pin and extending across said slot for limiting longitudinal motion of the coupling and actuating stem in the other direction, said spring ring also serving to prevent detachment of the pin from the slot.

ROBERT W. MUELLER.
HERBERT G. BERNSEE.
